(57) **CLAIM**

The ornamental design for a vent pipe protective cover, as shown and described.

DESCRIPTION

FIG. 1 is a top plan view of my vent pipe protective cover; FIG. 2 is a broken side elevation view of FIG. 1 identical in all directions;

FIG. 3 is a bottom plan view of FIG. 1;

FIG. 4 is a top plan alternate embodiment of my vent pipe protective cover;

FIG. 5 is a side elevation view of FIG. 4 identical in all directions;

FIG. 6 is an exploded view of FIG. 4 showing the installed relation to a roof vent pipe in phantom;

FIG. 7 is a bottom plan view of FIG. 4; and,

FIG. 8 is a perspective view of FIG. 4.

The broken line showing is for illustrative purposes only and forms no part of the claimed design.
